UNITED STATES PATENT OFFICE.

EDWARD H. HAVER, OF HOUSTON, TEXAS.

CAR-TRUCK.

No. 889,602.

Specification of Letters Patent.

Patented June 2, 1908.

Application filed June 1, 1907. Serial No. 376,880.

To all whom it may concern:

Be it known that I, EDWARD H. HAVER, a citizen of the United States of America, residing at Houston, in the county of Harris and State of Texas, have invented new and useful Improvements in Car-Trucks, of which the following is a specification.

This invention relates to car trucks, and one of the principal objects of the same is to provide an arrangement of equalizers which will reduce the lateral swinging motion of the car when passing around curves or when striking a slight obstacle, such as a slightly raised track end.

Another object of the invention is to provide compensating transverse equalizer bars for the truck frame and bolster which will reduce the swinging motion of the car frame.

These and other objects may be attained by means of the construction illustrated in the accompanying drawings, in which:

Figure 1 is a plan view of a car truck provided with my improvements. Fig. 2 is a side elevation of the same. Fig. 3 is a transverse sectional view on the line 3—3, of Fig. 1, looking in the direction indicated by the arrows in said figure. Fig. 4 is a longitudinal sectional view on the line 4—4 of Fig. 1, looking in the direction indicated by the arrows. Fig. 5 is a detail perspective view of the equalizers. Fig. 6 is a detail perspective view of one of the equalizer supporting bars. Fig. 7 is a detail perspective view of the bolster.

Referring to the drawings for a more particular description of my invention, the numeral 1 designates the truck frame, 2 are the journal boxes, 3 are the wheels, 4 are the bolster springs, 5 are the equalizer bars, 6 are the truss rods, and 7 are the truck springs. These parts may be of the usual or any suitable construction. The bolster 8 is provided with a pair of spaced supporting bars 9 secured to the upper side thereof by means of suitable brackets 10 connected to the sides of the bolster by means of screws or bolts 11, said bars 9 being connected at their ends by means of rods or pins 12, which pass through the bars 9 and through the upper ends of the brackets 10, said rods or pins having reduced ends 13, said ends being screw threaded. Connected to the reduced ends 13 are links 14, said links being held in place by means of nuts 15. The compensating or equalizing bars 16 are pivotally connected at their ends to links 17, said links being pivoted at their

upper ends to lugs 18 extending upward from a transverse supporting bar or plate 19 secured to the platform 20. The two equalizers 16 are pivotally connected centrally, as 60 at 21. The platform 20 is supported by rods 22, the ends of which are connected to links 23 pivotally connected at 24 to yokes or stirrups 25 bolted to the cross bars 26.

As shown in the drawings a pair of the 65 equalizers 16 are disposed upon opposite sides of the bolster 8, and connected thereto in the manner described. As a result of this construction and arrangement, the lateral vibration or swing of the car truck will be 70 sustained upon the compensating or equalizing bars 16 independently of the springs so that the jar of the car frame will be practically reduced to a minimum.

By means of my construction the swinging 75 motion of the car is materially reduced while the links 14 and 17 of the equalizing bars allow a certain degree of lateral motion, which is essential to the smooth and easy running of the car. The equalizers keep the 80 bolster and the springs always parallel, thus distributing the weight on both springs, instead of first on one side and then on the other.

From the foregoing it will be obvious that 85 by means of my invention, the rolling stock of passenger cars will be connected to lateral springs by equalizers which will absorb the swinging motion in passing around curves or upon uneven tracks; that the invention is 90 comparatively simple in construction, can be installed on passenger cars without material alteration in the structure of the truck, and will operate efficiently for the purpose referred to.

Having thus described the invention, what I claim is:

1. In a car truck, a pair of transversely disposed compensating or equalizing bars, said bars being pivotally connected together, 100 links at the ends of said bars, one pair of said links being supported upon the bolster, and the other pair upon a supporting bar connected to a platform under the bolster.

2. In a car truck, the combination of a 105 bolster, a pair of compensating or equalizing bars pivotally connected together and supported by links attached to the top of the bolster, said bars being supported upon links connected to a platform under the bolster. 110

3. In a car truck, a bolster, a platform under the bolster, supporting bars connected to

the top of the bolster, equalizers pivotally connected together and provided with links supported upon the bolster, and supporting bars on said platform to which the equalizers 5 are connected by links.

4. Compensating or equalizing bars for car trucks comprising flat bars pivotally secured together and having links pivoted to their outer ends, one pair of said links being 10 supported upon the bolster and the other pair upon a cross bar on the platform under the bolster.

5. In a car truck, the combination of a bolster, a platform supported under the bolster, 15 supporting equalizing bars connected to the upper side of the bolster, cross pins extend-

ing through said supporting bar and provided with reduced ends, bar links pivotally connected together, links connected to the ends of said equalizing bars, said links being 20 connected to the reduced ends of the cross pins, supporting bars having lugs at their opposite ends, and links connected to the equalizing bars and pivotally connected to said lugs. 25

In testimony whereof, I affix my signature in presence of two witnesses.

EDWARD H. HAVER.

Witnesses:

LUTHER M. WILSON,
S. BURCHARD.
